UNITED STATES PATENT OFFICE.

HARRY S. HART, OF CHICAGO, ILLINOIS.

DUMP-CAR.

1,389,350.

Specification of Letters Patent. Patented Aug. 30, 1921.

Application filed April 7, 1919. Serial No. 288,049.

To all whom it may concern:

Be it known that I, HARRY S. HART, a citizen of the United States, residing at Chicago, in the county of Cook and State of Illinois, have invented certain new and useful Improvements in Dump-Cars, of which the following is a specification.

My invention relates to freight cars of the type commonly known as hopper cars, which are used very largely for the transportation of coal or like dumpable material; and has among its objects the improvement of this type of car in the manner to greatly increase the load carrying capacity of the car without changing its overall dimensions, and to provide such a car from which the load may be quickly discharged with a minimum amount of labor, the car being practically self-cleaning.

With these and other objects which herein-after will be pointed out, the invention consists of the combination and details described in the following specification and claims.

The invention is illustrated on the accompanying sheets of drawings, in which—

Figure 1 is a fragmentary side elevation of a dump car embodying my invention;

Fig. 2 is a transverse sectional view of the same car taken over the trucks; and

Fig. 3 is a transverse sectional view of the same car taken intermediate the trucks.

It has been customary to build hopper cars for the transportation of coal and like commodities, having inclined end portions over the trucks discharging the load through the center of the car by means of cross hoppers or longitudinal hoppers provided with suitable dump doors. These prior constructions are well known and require no particular description for an understanding thereof. Owing to the location of the inclined end portions over the trucks, those portions of the cars at the ends are largely useless for load carrying, so that any attempt to increase the capacity of these cars necessarily has been by a lengthening of the car or by increasing its height, while the discharge of the load through the car hoppers is difficult, even where special unloading stations are provided, owing to the necessarily restricted door openings provided in the cross hoppers. While longitudinal hoppers also have been provided in cars of this type for discharging the load at the sides in a manner to make unloading easier, at-

tempts to apply this principle to the car have resulted in a greatly decreased load carrying capacity.

By my present invention, I overcome the difficulties heretofore experienced in this type of car, making it possible to carry in the car of the same length a greatly increased load, and at the same time making it possible to discharge the load at a greatly reduced expenditure of time and labor.

The body of the dump car, which is carried on trucks including wheels 11 at each end of the car, comprises sides 12, ends 13, and a floor 14. The sides 12 of the car are high plate girder sides, which carry the vertical load. These sides are connected by rigid cross frame members 20. The floor over the trucks comprises a stationary flat portion over the center sill 16, said floor portion extending continuously from one side of the car to the other. Associated with these stationary flat floor portions over the trucks are side dump doors 15, which may be as shown, pivotally mounted in and form parts of the sides of the car. By means of these side dump doors, most of the load over the trucks will be self-dumping. Normally these side dump doors are locked in closed position by locking fingers 18 mounted upon suitably operated shafts 19. When the load over the trucks is to be dumped, the shafts 19 are rotated, whereby the fingers release the doors, which are forced open by the pressure of the dumpable material.

The floor intermediate the trucks is the same as that shown and described in my co-pending application, Serial No. 260,927, filed November 4, 1918, now Patent No. 1,300,962, dated April 15, 1919, and includes stationary portions 17 which extend downwardly and inwardly from the lower edges of the car sides 12 toward the center of the car, said stationary portions 17 extending to a point and generally being located below the stationary floor portions 14 over the trucks, the lower edges of the stationary floor portions 17 terminating in a plane considerably below the center sill 16.

By means of the sloping members 17, 105 which are connected to the cross beams adjacent the trucks, the resistance of the car to the well-known racking strains to which cars are ordinarily subjected, is greatly increased, and such strains are overcome in an efficient manner.

Coöperating with the downwardly and in-

wardly sloping floor portions 17 intermediate the trucks are flat dump doors 22, which are located in a plane considerably below the center sill 16 and which, when in closed position, as shown in full lines in Fig. 3, connect the lower edges of the floor members 17 and the lower edges of the side hopper members 23 which extend vertically downward from the center sill 16. These doors 10 are located at as low a level as is practicable in order to increase the capacity of the car. Owing to this low position of these doors, it is not advisable to hinge them at their edges because of clearance conditions. It is 15 preferable, therefore, that the doors should be opened by sliding them bodily from beneath the load. One way in which this may be done I illustrate. In the present exemplification of my invention, I show the doors 20 as pivoted at a point above the horizontal door portions so as to swing bodily, that is, these flat dump doors 22 preferably are suspended pendulum-like from frame members at pivotal centers 24, there being at the ends 25 of the doors end plate members 25 forming hangers. It will be understood, of course, that as shown these hangers may be mounted outside the end walls 25' of the longitudinal hoppers 26 intermediate the trucks and 30 on opposite sides of the longitudinal center of the car. When in closed position, as shown in Fig. 3 of the drawings, the flat doors form tight seals with the lower edges of the floor portions 17 and the vertical members 23, and may be held in such position by any suitable door operating mechanism.

One example of the above mechanism as shown in Fig. 3 includes a center operating shaft 27 and operating chains 28, which 40 operatively connect the shaft 27 with the doors 22. It will be noted that the centers 24, from which the doors 22 are hung, are located off-center with respect to the longitudinal center line of the doors 22, so that 45 when the operating shaft 27 is operated in a manner to slacken the chains 28 or unwrap them from the shaft 27, the doors 22 will swing outwardly as a result of their own weight, and this outwardly swinging movement will be made more positive as a result 50 of the weight of the load to be dumped. One of these dump doors 22 is shown in opened or dumping position in dotted lines in Fig. 3. To close the dump doors, it is merely 55 necessary to actuate the operating shaft in a manner to wrap the chains 28 thereon, whereupon the dump doors 22 will move into a closed position.

By means of placing the flat dump doors 60 22 in a horizontal plane when in closed position and at a level as far below the center sill as is permissible, the capacity of the dump car is greatly increased, it being appreciated also that by means of the floor

construction over the trucks, the capacity of 65 the car is also increased. At the same time, by means of the floor and dump door arrangement, the car is made practically self-clearing. Furthermore, with the high plate girder sides carrying the loading, said sides 70 being tied together by rigid cross members, the end floor portions over the trucks being stationary and rigid as also are the intermediate floor portions 17, a very strongly constructed car is provided, not only for carrying the load, but also for resisting all strains 75 including buffing strains.

It is my intention to cover all modifications falling within the spirit and scope 80 of the following claims.

I claim:

1. A car of the class described, having high girder sides carrying the load, the floor over the trucks comprising a stationary horizontal flat portion, the floor intermediate 85 the trucks being at a lower level than the floor portions over the trucks, side dump doors formed within the area of the girder sides and associated with the floor portions over the trucks, and floor dump doors intermediate the trucks whereby the load may be dumped.

2. A car of the class described, having high girder sides carrying the load, the floor over the trucks comprising a stationary horizontal flat portion, the floor intermediate the trucks being at a lower level than the floor portions over the trucks, doors mounted in the high girder sides of the car adjacent the flat floor portions over the trucks, whereby 100 the load over the trucks may be discharged to the sides of the car, and dump doors in the floor of the car intermediate the trucks for dumping the intermediate portion of the load.

3. A car of the class described, having high girder sides carrying the load, the floor over the trucks comprising a stationary horizontal flat portion, the floor intermediate the trucks being at a lower level than the floor portions over the trucks, doors in the girder sides whereby the load over the trucks may be dumped outwardly and means whereby the load intermediate the trucks may be dumped inwardly.

4. A car of the class described having high girder sides and end walls, a substantially horizontal flat floor over the trucks, the floor between the trucks comprising hoppers at a lower level than the end floor portions, means above the lower level of the girder sides for discharging the load from said end floor portions and means for discharging the load from said hoppers.

Signed at Chicago, Illinois, this 5th day of 125 April, 1919.

HARRY S. HART.
